UNITED STATES PATENT OFFICE.

FREDERICK REUTER, OF BROOKLYN, NEW YORK, ASSIGNOR TO JOHN C. GRAHAM, OF PHILADELPHIA, PENNSYLVANIA.

DESIGN FOR FRINGE.

SPECIFICATION forming part of Design No. 13,127, dated August 1, 1882.

Application filed June 16, 1882. Term of patent 14 years.

To all whom it may concern:

Be it known that I, FREDERICK REUTER, of Brooklyn, State of New York, have invented and produced a new and original Design for 5 Fringe, of which the following is a specification, reference being had to the accompanying drawing, forming part thereof.

The drawing represents in front elevation a fringe which illustrates my design, which design consists in a fringe having a heading, A, of any suitable kind, to which is attached at intervals chenille pendants, B, of substantially cylindrical contour. The pendants B are each longitudinally divided into blocks of two or 10 more colors in such manner that the adjacent blocks of color on any one pendant, as well as the adjacent blocks of color of any two adja-

cent pendants, are dissimilar, with the result that a series of such pendants displays a checker-board pattern, as shown in the drawing. 20

I claim—

A design for fringe consisting of a heading and a series of chenille pendants, each of which pendants is so divided longitudinally by two 25 or more colors, and so arranged with respect to its adjoining pendant, as to form a checker-board pattern, substantially as set forth.

In testimony whereof I have hereunto signed my name this 12th day of June, A. D. 1882.

FREDERICK REUTER.

In presence of—

W. K. SHRYOCK,
CLEMENT CRESSON.
